UNITED STATES PATENT OFFICE.

CHARLES E. GALT, OF PHILADELPHIA, PENNSYLVANIA, ASSIGNOR TO
DAVIS & GALT, OF SAME PLACE.

DESIGN FOR A HANDLE FOR FORKS, SPOONS, OR SIMILAR WARE.

SPECIFICATION forming part of Design No. 20,545, dated March 3, 1891.

Application filed January 7, 1891. Serial No. 377,044. Term of patent 7 years.

To all whom it may concern:

Be it known that I, CHARLES E. GALT, a citizen of the United States of America, residing at Philadelphia, in the county of Philadelphia, 5 and in the State of Pennsylvania, have invented and produced a new and original Design for Flat Ware; and I do hereby declare that the following is a full, clear, and exact description thereof, reference being had to the accompanying drawings, in which—

Figure 1 shows a perspective view of the front or top of a fork or spoon handle made in accordance with my invention; Fig. 2, a similar view of the back of the handle, and 15 Fig. 3 a view of a section on line xx of Fig. 1.

Letters of like name and kind refer to like parts in each of the figures.

The object of my invention has been to produce a new ornamental and attractive design 20 for the handles of forks, spoons, knives, &c.; and to this end my invention consists in the design as hereinafter specified.

As shown in the drawings, the leading features of my design are the plain swelled center 25 A and the ornamented border B to contrast with such center. At the upper end of the center, on the back of the handle, a tip C is shown; but it is not a material feature of the design. To increase the contrast between the 30 center and border, the latter is raised above the neighboring plain surface of the former. Along the border's inner edge or the outer edge of the center runs a thread D, terminating with the border at the lower end of the 35 handle.

In a handle for forks, spoons, knives, and the like formed in accordance with my design the ornamented border and plain swelled center are found to be so contrasted as to produce a very rich and pleasing effect. The 40 raising of the ornamented surface of the border above the adjoining parts of the face of the swelled center increases the contrast, so as to improve the effect and give the handle a most attractive appearance. 45

Having thus described my invention, what I claim is—

1. A design for the handles of spoons, forks, knives, and the like, comprising a plain center swelled on the front and back and an ornamental border, as herein described and shown. 50

2. In a design for the handles of spoons, forks, knives, and the like, the front face consisting of a plain swelled center and a raised ornamented border, as herein described and 55 shown.

3. In a design for the handles of spoons, forks, knives, and the like, the back consisting of a swelled center and an ornamented border, as herein described and shown. 60

In testimony that I claim the foregoing I have hereunto set my hand this 30th day of December, 1890.

CHARLES E. GALT.
